UNITED STATES PATENT OFFICE

WALLACE S. WARNOCK, OF CHICAGO, ILLINOIS

PRINTING-PRESS BED

Application filed February 27, 1928. Serial No. 257,407.

My invention relates to beds either of the flat or rotary type for supporting and holding printing plates or forms and particularly to those beds which are provided with grooves that receive the base portions of form or plate engaging clamps that are commonly termed "register hooks" and which grooves contain elongated gears which cooperate with gear elements upon the bodies of the clamps or register hooks whereby such clamps or register hooks may be caused to travel in the grooves to bring the clamping jaws thereof into or out of engagement with the plates or forms upon the beds.

Instead of casting the elongated gears integrally with the bed, as illustrated in my copending application, Serial No. 257,406, filed February 27, 1928, I form the elongated gears separately from the bed and maintain them in assembly with the bed by means of key retaining bars. Either or both the gears and bars are preferably of wedging formation and the bed is provided with shoulders, in the gear receiving grooves, which overhang the elongated gears and constitute abutments against which the gears are forced by the action of the retaining bars whereby the gears are rigidly secured in place. There are desirably two gears in each groove and these gears are spaced apart to afford a clearance therebetween into which the foreign matter may be discharged from the gears and from which the foreign matter may be removed by a suitable tool.

The invention will be more fully explained by reference to the accompanying drawings in which Fig. 1 is a plan view of a portion of a bed together with a printing plate thereof held by means of register hooks or clamps; Fig. 2 is a side view of the parts shown in Fig. 1; Fig. 3 is a sectional view on line 3-3 of Fig. 1 on a larger scale; Fig. 4 is a sectional view on line 4-4 of Fig. 1 on a larger scale; Fig. 5 is a sectional view on line 5-5 of Fig. 4; Fig. 6 is a sectional view on line 6-6 of Fig. 4; Figs. 7, 8, 9 and 10 are cross sectional views respectively illustrating other forms of the invention; Fig. 11 shows a bed in the form of a cylinder, one spiral groove being fully illustrated as it appears on one

side of the cylinder; and other spiral grooves being suggested; and Fig. 12 is a sectional view on line 12-12 of Fig. 11.

The body of the clamp illustrated is composed of an L-shaped member 1 and a U-shaped member 2 one of whose sides 3 engages the upright side of the member 1. An assembling bolt 4 passes through the ends of the U-shaped member 2 and is threaded into the upright side of the L-shaped member 1. Another assembling bolt or screw 5 passes through the outer end of the top side of the L-shaped member 1 and enters the U-shaped member 2, this bolt being threaded into said U-shaped member. The work engaging jaw 6 is formed with a stem 7 which is journaled in the top side of the clamp body 1. A cam 8 is fastened upon the lower end of the stem 7, this cam constituting a flange whose upper face is in contact with the lower face of the top side of the body member 1, being maintained in this relation by a shoulder 9 which contacts with the top face of said top side of the body member 1. Such lower face of this body member is raised to a depth less than the thickness of said cam and just sufficient to snugly receive the adjusting plate 10 which is slidable longitudinally of the clamp body. This plate is pressed upon by a leaf spring 11 which is clamped by the head of the bolt 4 against the clamp body. The spring serves to maintain the reduced end 10' of the plate 10 in engagement with the cam 8. Said cam has two diametrically opposite arcuate dwells 8' that are coaxial with the jaw stem 7. It also has two diametrically opposite concave actuating portions 8'' that are located between the parts 8'. When either of the dwells 8' engages the plate portion 10', the plate 10 is thrust outwardly from the axis of the jaw 6 against the force of the spring 11 and when either cam portion 8'' receives the plate portion 10', the plate 10 is moved toward the stem of the jaw by the spring 11 to the extent permitted by the cam.

The adjusting plate 10 is formed with depending fingers 10'' that enter the slots or recesses 12' in the retaining plates 12 which are employed to hold the body of the clamp

within the groove 13 of the bed or form support 14, the plates 12 being movable transversely of the clamp body and being projectable laterally thereof at their longitudinal sides in order that they may serve to hold the clamp in assembly with the bed. The upper sides of said retaining plates 12 are formed with recesses 12² which receive the arcuate portions 8² of the cam 8 whereby said plates are prevented from being moved lengthwise of the clamp body. The slots or recesses 12¹ in each retaining plate 12 are slanted as illustrated whereby the adjusting plate 10 has wedging engagement with the retaining plates. When the jaw 6 is placed lengthwise of the clamp body, the cam portions 8² are positioned so that one of them fully receives the adjusting plate portion 10¹, the wedging fingers 10² then causing the retaining plates to move together to bring the outer longitudinal edges of these plates flush with the sides of the clamp body. When these retaining plates are thus drawn inwardly toward each other, the clamp body 25 may be inserted into the selected one of the parallel grooves 13 formed in the bed support 14, this groove being of just such depth as to bring the plates 12 into the plane of the slots 15 formed in the sides of the groove 13, these slots being just of sufficient depth to snugly receive the outer longitudinal sides of these plates when the jaw 6 is turned into a plate holding position, the jaw, in being brought into its plate holding position, forcing the adjusting plate 10 outwardly until its cam engaging portion 10¹ is engaged by one of the dwells 8². The plate holding jaw 6 is then held from vertical displacement and close to the work support 14 to take part 30 in holding the plate or work 16 close upon its support.

The clamping device is also adjustable in the groove 13 that receives it so that its location may be readily changed to suit the location of the printing element 16. The clamping device illustrated includes a worm screw 17 which coats with elongated fixed gears 18 in the bottom of the corresponding groove, these gears 18 being hereinafter more fully described. The worm screw 17 is mounted upon the stem of the bolt 4 and is free to turn on and with respect to said bolt stem, said worm screw being in thrusting relation to the body of the clamp so that when the screw is turned the clamp will be forced to move along the groove in which its body is received. Said screw is turned by means of two intermeshing bevel pinions 19 and 20, the pinion 19 being housed by the body member 22 and rotatable therein while the pinion 20 is directly formed upon the body of the screw 17. The pinion 19 is coaxial with the jaw stem 7. Said jaw stem is provided with a cylindrical bore 21 while the pinion 19 is 45 provided with a square bore 22 that is in

alignment with the bore 21. A square wrench may be passed through the bore 21 into the bore 22 in order to turn the pinion 19 to turn the screw 17 and force or effect the travel of the clamp.

In the use of the clamping device, the body thereof is placed in the groove 13 that receives it in close proximity to the work that is to be held, the actual clamping engagement of the clamping jaw with the work being effected by turning the screw 17 in the manner described.

Each of the two gears 18 in the bottom of each groove 13 is somewhat in the form of a rack, being constituted of a row of teeth which are in fixed relation to the bed 14 and which gears are separately formed and thereafter assembled with the bed in accordance with my present invention. The teeth of each of the two gears 18 are helically inclined and have their crowns curved upon an axis extending along the groove, the teeth of each of two fixed gears in a groove being spirally aligned with the teeth of the other fixed gear so that the teeth of each gear are, in effect, 90 continuations of the teeth of the other. In other words, the gears 18 are of arcuate curvature, the gears having a common center or axis of curvature which is coincident with the axis of the worm 17. The thread of the worm 17 is thus placed in very intimate contact with the teeth of the gears 18, the engagement of the worm thread with the teeth of the gears 18 being full throughout the arcuate lengths of said gear teeth.

Referring to the form of the invention shown clearly in Figs. 3 and 4, the teeth 18 are provided upon the inner and upper corner portions of bars 23 whose body portions are overhung by shoulders 24 formed in the bed. The adjacent sides of said bars are spaced apart to form a channel 25 in which foreign matter that descends into the groove and which is dislodged from the fixed gears in the groove may be received. The lower and adjacent corners of the bars 23 may be formed with wedging faces 26 which converge upwardly. A retaining bar 27 is inserted between the wedging faces 26, this retaining bar desirably also having wedging faces that engage and slope respectively similarly to the wedging faces 26. Said retaining bar is forced into place and serves, when being forced into place, to force the gear bars 23 outwardly and upwardly and into tight engagement with the shoulders 24 above the gear bars and the sides of the elongated part of the corresponding groove that are alongside of the gear bars. My new construction is a decided improvement over the prior structures as it enables the elongated gears to be separately formed and accurately placed and permits them to be replaced when any of the gears thereon become broken.

The structure shown in Fig. 7 employs a

retaining bar 28 which serves to spread the gear bars 23' laterally apart, the lower and outermost corners of the gear bars 23' having wedging faces 26' as do also the portions of the bed 14 which are opposed by said faces 26'. Said wedging faces upon said gear bars 23' converge downwardly as do also the opposed wedging faces upon the bed whereby said gear bars are forced to rise as they are spread apart by the retaining bar 28. The tops of the gear bars 23' engage the shoulders 24' that are formed in the bed and which overlie said gear bars.

In the structure of Fig. 8 there is a single gear bar 29 in which both sets of gear teeth 18 are cut. The upright sides of the gear bar 29 are of step formation to be engageable with shoulders 30 and 31 formed on opposite sides of the groove 13' which generally corresponds to the groove 13 hitherto described. The retaining bar 32 is forced beneath the gear bar 29 to force this gear bar into engagement with the shoulders 30 and 31.

The structure of Fig. 9 is generally similar to the structure of Fig. 8 except that the single gear bar 29 of Fig. 8 is replaced by the two gear bars 29' and also with the exception that the retaining bar 32' is formed with ribs 32' that are received in grooves 30 formed in the bottoms of the bars 29'.

In the structure of Fig. 10 the single elongated gear bar 33 carries a single row of gear teeth 34 which are illustrated as being of helical curvature concentric with the axis of the particular clamping worm 17 that is within the groove. The gear bar 33 is held tightly in place by the retaining bar 35. The portions of the gear bar 33 which margin its longitudinal edges and the adjacent portions 40 of the bed 14 have interengaging hook formations 33', 14' whereby said gear bar is rigidly held in place.

Changes may be made without departing from the invention.

Having thus described my invention, I claim:

1. A printing bed having a groove formed therein for receiving the body portion of a plate engaging clamp, in combination with an elongated gear inserted within said groove, and a retaining bar inserted between the bottom of the groove and a lower portion of said gear to position such gear.

2. The structure of claim 1 wherein the retaining bar is of wedge formation where it engages the gear to force the gear into position.

3. The structure of claim 1 wherein the elongated gear has a wedging face that is engaged by the bar whereby the gear is forced into position.

4. The structure of claim 1 wherein the faces of the bar and gear that are in engagement are both wedging to force the gear into place.

5. A printing bed having a groove formed therein for receiving the body portion of a plate engaging clamp, in combination with an elongated gear inserted within said groove, the bed also having a shoulder overhanging the gear and engaging the same to position it, and a retaining bar inserted between the bottom of the groove and a lower portion of said gear to position such gear against the shoulder.

6. The structure of claim 5 wherein the retaining bar is of wedge formation where it engages the gear to force the gear into position.

7. The structure of claim 5 wherein the elongated gear has a wedging face that is engaged by the bar whereby the gear is forced into position.

8. The structure of claim 5 wherein the faces of the bar and gear that are in engagement are both wedging to force the gear into place.

In witness whereof, I hereunto subscribe my name.
